[57] CLAIM

The ornamental design for a massager-exerciser for neck and back, as shown and described.

DESCRIPTION

FIG. 1 is a top plan view of a massager-exerciser for neck and back showing my new design;

FIG. 2 is a front elevational view thereof;

FIG. 3 is a bottom plan view thereof;

FIG. 4 is a left side elevational view thereof;

FIG. 5 is a right side elevational view thereof;

FIG. 6 is a top plan view of a second embodiment of the design of FIGS. 1 through 5;

FIG. 7 is a top plan view of a third embodiment of the design of FIGS. 1 through 5; and

FIG. 8 is a front elevational view of the design shown in FIG. 7.
